UNITED STATES PATENT OFFICE.

AUGUST H. SCHIERHOLZ, OF SAN FRANCISCO, CALIFORNIA.

ORE-CRUSHER.

SPECIFICATION forming part of Letters Patent No. 531,068, dated December 18, 1894.

Application filed March 26, 1894. Serial No. 505,127. (No model.)

To all whom it may concern:

Be it known that I, AUGUST HENRY SCHIERHOLZ, of San Francisco, in the county of San Francisco and State of California, have invented a new and Improved Ore-Crusher, of which the following is a full, clear, and exact description.

The invention relates to ore crushers, such as shown and described in the application for Letters Patent of the United States, Serial No. 494,512, filed by me December 23, 1893.

The object of the present invention is to provide a new and improved ore crusher, in which a uniform wear of the grinding surfaces is obtained and the centrifugal strain on the thrust bearings of the crushing rolls is greatly reduced, to permit of driving the machine with considerably less power and without decreasing the capacity of the machine.

The invention consists of certain parts and details, and combinations of the same, as will be fully described hereinafter and then pointed out in the claims.

Reference is to be had to the accompanying drawings, forming a part of this specification, in which similar letters of reference indicate corresponding parts in all the figures.

Figure 1 is sectional side elevation of the improvement. Fig. 2 is a plan view of the same. Fig. 3 is a transverse section of the same on the line 3—3 of Fig. 2. Fig. 4 is an enlarged transverse section of the bearings for the crushing rolls on the line 4—4 of Fig. 1. Fig. 5 is a plan view of one of the end thrust bearings, showing it made in sections. Fig. 6 is a sectional side elevation of a modified form of the improvement; and Fig. 7 is an enlarged transverse section of part of the same on the line 7—7 of Fig. 6.

The improved ore crusher is provided with a circular pan A, having inclined sides, a feed spout A' and a discharge spout A² for carrying off the crushed material. The pan A is supported on a suitable foundation B, and in the sides of the said pan are openings covered by screens A³, discharging into the said spout A²; as is plainly illustrated in the drawings.

In the bottom of the pan A is arranged a circular die C, on which travel the crushing rolls D, adapted to crush the material placed

on the said die C. The crushing rolls are either fastened on the axles E, as illustrated in Figs. 1, 2 and 3, or are mounted to rotate loosely on the axles E', as illustrated in Figs. 55 6 and 7. Each axle E is journaled in the bearings F and G, of which the bearing F is located near the respective roll D, and is mounted to slide vertically in suitable guideways in a frame or table H, secured on the driving shaft I disposed vertically and mounted to turn in suitable bearings in the machine. The other bearing G is provided with trunnions G', mounted to turn in suitable bearings in the frame or table H, as is plainly 65 shown in Fig. 4, so that the roll D can move up or down according to the amount of material on the die C, the bearing F as above stated sliding up and down in suitable guideways on the frame H, while the bearing G 70 rocks on its trunnions.

As illustrated in Fig. 2, the two axles E for the two crushing rolls D extend on opposite sides of the driving shaft I, so that the said axles extend tangentially to the said driving 75 shaft instead of radiating therefrom, as shown and described in the application for Letters Patent above referred to. Each bearing G is constructed in such a manner as to receive annular shoulders formed on the corresponding axle E, whereby all end thrust of the axle E is taken up by the corresponding bearing G.

As illustrated in Figs. 1, 2 and 3, the driving shaft I, is connected by gear wheels with 85 the main shaft J, carrying pulleys connected by a belt with other suitable machinery for imparting a rotary motion to the said main shaft J. The latter transmits its motion to the vertical drive shaft I carrying the frame 90 H, so that the latter in revolving with its shaft I, carries around the axle E, so that the rolls D roll off on the die C, and thereby crush the material placed on the latter.

On the frame H are held adjustably the 95 usual scrapers K, operating over the circular die C, and in order to keep the screens A³ free from clogging material, I provide the water pipe N, connected with a water reservoir O, supported on the upper end of the 100 driving shaft I. Thus, as the latter rotates the pipe N is carried around and delivers a

stream of water on the said screens A³, to prevent their clogging, and at the same time to wash the material through the screens into the circular outlet chute A².

- 5 In the modified form illustrated in Figs. 6 and 7, the shaft E' for the crushing roll D' is held in a vertically sliding bearing F', fitted in suitable guideways in the frame H', the outer end of the axle E' being provided with a 10 transversely extending pivot pin E², mounted to turn in suitable bearings in the frame H', so that the said axle E' is free to swing up and down, but is prevented from turning. As previously mentioned, the roll D' is mounted 15 to rotate loosely on this axle E', so that the latter does not require turning except to be carried around with the frame H' held on the shaft I'.

Having thus fully described my invention, 20 I claim as new and desire to secure by Letters Patent—

1. In an ore crusher, the combination with a pan, and a vertical and rotary shaft, of a frame secured to the upper end of the said 25 shaft, a vertically sliding bearing at each end of the frame, a trunnion mounted at each end of said frame, the trunnion at one end of the frame being opposite the sliding bearing at the opposite end of the frame, parallel shafts 30 mounted in the said bearings and trunnions,

and a crushing roller on one end of each shaft, substantially as described.

2. An ore crusher, comprising a ring-shaped pan provided with screen covered openings, a central vertical and rotary shaft projecting 35 above the pan, a frame secured to the upper end of the shaft, a vertically sliding and a pivoted bearing at each end of the frame, the sliding bearings being opposite the pivoted bearings, parallel shafts mounted in the said 40 bearings, a crushing roller on one end of each shaft, and a scraper secured to the frame and projecting into the pan, substantially as described.

3. An ore crusher, comprising a ring-shaped 45 pan provided with screen covered openings, a vertical and rotary shaft, a tank supported on the upper end of the shaft, a pipe leading from the tank to the pan, a frame secured to the said shaft below the tank, a vertically 50 sliding and pivoted bearing at each end of the frame, two parallel shafts mounted in the said bearings, a crushing roller on one end of each shaft, and a scraper secured to the frame and projecting into the pan, substantially as herein shown and described.

AUGUST H. SCHIERHOLZ.
